UNITED STATES PATENT OFFICE.

NATHAN JAMES WHITAKER, OF AMSTERDAM, NEW YORK.

COLLAR.

1,021,283.

Specification of Letters Patent. Patented Mar. 26, 1912.

Application filed January 16, 1911. Serial No. 602,882.

To all whom it may concern:

Be it known that I, NATHAN J. WHITAKER, a citizen of the United States, residing at Amsterdam, in the county of Montgomery and State of New York, have invented a new and useful Collar, of which the following is a specification.

This invention relates to a turn-down collar and has for its principal object to provide improvements whereby the scarf or necktie can be readily adjusted without the button at the rear of the collar interfering with the free movement of the tie.

A further object of the invention is the provision of a tab or tongue formed in the middle of the collar at the rear for receiving the collar button for attaching the collar to the collar band of the shirt, while at the same time maintaining the proper set of the collar and permitting the necktie to slide freely around in the collar.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a perspective view of the improved collar. Fig. 2 is a plan view of the outer section of the collar drawn on a reduced scale. Fig. 3 is a similar view of the inner section of the collar. Fig. 4 is a transverse section on line 4-4, Fig. 1. Fig. 5 is a sectional view of a modified form of the invention.

Similar reference characters are employed to designate corresponding parts throughout the views.

The collar A, Fig. 1, is preferably made of a plurality of sections which vary in number according to the plies of the collar. In the present instance, I have elected to illustrate a two-ply collar made of sections a and b, Figs. 2 and 3, which are cut from the same pattern and each preferably made in one piece and folded on the line 1. The band portions 2 of the sections have the button holes 3 and the outer section a of the collar is provided with a longitudinally-extending slot 4 in its band portion 2 adjacent the middle thereof, while the corresponding portion of the inner section b of the collar is formed with a tongue or tab 5 cut out

from the stock so as to extend through the slot 4 when the two sections are put together and stitched. This tab 5 has a buttonhole 6 for receiving the rear button of the shirt, and the under portion 7 of the outer section a under the tab 5 bears against the head of the button 8, as shown in Fig. 4. After the two sections of the collar are assembled, they are stitched around the edges, as shown at 9, Fig. 1, and the two sections are also stitched around the slot 4 so as to strengthen the collar at the tongue. With a collar constructed in this manner, the button tongue or tab 5 forms an integral part of one of the inner sections of the collar and the collar can be readily applied to the shirt because of the flexibility of the tongue, and at the same time, the button is prevented from binding on the scarf or necktie, as is commonly the case, so that with the present arrangement, the scarf or necktie can be adjusted with ease. It will be understood that any number of sections may be used, according to the number of plies desired.

In the modified form of the invention shown in Fig. 5, the tab 5' is separate from and stitched to the inner section b of the collar, and projects through the slot 4' of the outer section.

From the foregoing, it is thought that the construction, operation and many advantages of the herein described invention will be apparent to those skilled in the art without further description, and it will be understood that various changes in the size, shape, proportion and minor details of construction, may be resorted to without departing from the spirit or sacrificing any of the advantages of the invention.

Having thus described the invention, what I claim as new, and desire to secure by Letters Patent, is:—

1. A collar composed of inner and outer sections constituting plies, the outer section having a slot in its band portion at the center below the upper edge, the inner section having an integral tongue extending outwardly through the slot and depending therefrom, said tongue being backed up by the adjacent portion of the outer section and terminating short of the bottom edge of the collar, and having a buttonhole for attaching the collar to a shirt.

2. A turndown collar formed of a plurality of sections constituting plies, each section being of the same contour and hav-

ing a band portion and an integrally connected turned down portion, said sections being placed one upon the other and stitched together around all the edges, the outer section having a slot in its band portion at the center below the top edge, and a tongue provided with a button hole for attaching the collar to a shirt, said tongue being provided on an inner section and passed through said

slot and depending therefrom but terminating short of the bottom edge of the collar. 10

In testimony that I claim the foregoing as my own, I have hereto affixed my signature in the presence of two witnesses.

NATHAN JAMES WHITAKER.
